UNITED STATES PATENT OFFICE.

MANOOG KAZANJIAN, OF BOSTON, MASSACHUSETTS.

DESIGN FOR A PHONOGRAPH-RECORD.

55,053.

Specification for Design.

Patented May 4, 1920.

Application filed September 8, 1919. Serial No. 322,561. Term of patent 14 years.

To all whom it may concern:

Be it known that I, MANOOG KAZANJIAN, a citizen of the United States, residing at Boston, county of Suffolk, State of Massachusetts, have invented a new, original, and ornamental Design for Phonograph-Records, of which the following is a specification, reference being had to the accompanying drawing, forming part thereof.

The figure is a plan view of a phonograph record, showing my new design.

I claim:

The ornamental design for a phonograph record, as shown.

MANOOG KAZANJIAN,
